UNITED STATES PATENT OFFICE.

MELTON MORRIS, OF DUTTON, ALABAMA.

FEED-REGULATOR.

1,217,621.

Specification of Letters Patent. Patented Feb. 27, 1917.

Application filed July 10, 1913. Serial No. 778,320.

To all whom it may concern:

Be it known that I, MELTON MORRIS, a citizen of the United States, and a resident of Dutton, in the county of Jackson and State of Alabama, have invented certain new and useful Improvements in Feed-Regulators, of which the following is a specification, reference being had to the accompanying drawing.

10 This invention relates to improvements in feed regulators employed in connection with grinding mills designed more particularly for the purpose of producing a fine grade of corn meal and one of the principal objects 15 of the invention is to provide simple, reliable and efficient means for adjusting the grinding stones and for providing means for shaking the hopper.

Still another object of the invention is to 20 provide means for regulating the feed of the material to be ground, the feeding means being also utilized for shaking the bottom of the hopper to insure a continuous and uniform supply of corn to the grinding mechanism.

These and other objects may be attained by means of the construction illustrated in the accompanying drawings, in which:

Figure 1 is a side elevation of a grinding 30 machine made in accordance with my invention;

Fig. 2 is a top plan view of the same;

Fig. 3 is a vertical sectional view taken lengthwise of the main shaft;

35 Fig. 4 is a detail vertical sectional view taken through the hopper and its shaking bottom;

Fig. 5 is a detail sectional view showing the discharge spout;

40 Fig. 6 is a detail view showing the means for adjusting the grinding stones, one relatively to the other for grinding coarse and fine material.

Referring to the drawings for a more particular description of the invention, the numeral 1 designates the corner posts or uprights of the machine and 2 are the cross bars connecting the uprights and forming a frame for supporting the mechanism. For 50 holding the frame firmly together, brace rods 3 are employed. A shaft 4 is horizontally mounted in the frame and at one end of the shaft outside the frame is a driving pulley 5. On the shaft 4 is a feeding device 55 comprising an enlarged collar 6, having spirally formed spaced feeding ribs 7. The

shaft 4 is provided with a ball bearing collar 8 and connected to said collar are L-shaped bolts 9 which extend through a bearing plate 10 mounted on one of the bars 2. 60 A spiral spring 11 bears against the collar 8 and against the plate at its opposite end. The tension of the spring 11 may be adjusted by means of the nuts 12 on the bolts 9. A ball bearing cone 13 is secured to the shaft 65 4 by means of a binding screw 14 and the bearing balls 15 are disposed between the cone 13 and the collar 8. It will thus be seen that a slight movement of the shaft 4 will be taken up by the spring 11. The collar 6 limits the movement of the shaft 4 in one direction.

The rotating grinding stone 16 is fast on the shaft 4 and the stationary stone 17 is mounted in the framework of the machine. 75 The casing 18 is provided with a downwardly inclined discharge spout 20 as shown more clearly in Figs. 2 and 5.

One end of the shaft 4 is mounted in a bearing block 21 and a metal plate 22 bears 80 against the end of the shaft 4 as shown more clearly in Fig. 6, said plate being mounted in a slot or recess 23 in the bearing block 21. Set screws 24 extend through the forward end 25 of the bearing block 21, said set 85 screws bearing at their inner ends against the plate 22 to adjust the shaft 4 longitudinally and to regulate the distance between the stones 16 and 17 for grinding fine or coarse material. A hand wheel 26 is provided with a threaded stem 27 which bears 90 against the plate 22 between the two set screws 24.

The hopper 28 is positioned low on the machine and is provided with a cut off 29 95 which can be operated by means of a pivoted lever 30 to regulate the feed of the corn through the opening 31. The feed opening of the hopper is located forward of the collar 6. The hopper ends in an oblique front 100 bottom portion α , as shown in Fig. 3.

Connected to the oblique bottom portion of the hopper is a shaking tray or member 32, said tray being connected to the hopper by means of a bolt or pivot 33 which passes 105 through the oblique front portion of the tray, while the opposite end of the tray is provided with an enlargement or lip 34 on the under side of the inner end thereof in the path of the ribs 7 and when the shaft 4 is rotated the tray 32 is shaken up and down 110 by means of the ribs 7 as will be obvious.

It will be seen that the tray 32 is supported at the forward end by means of the pivot 33, and at its rear end by means of the lip which rides upon the collar and ribs.

5 From the foregoing, it will be apparent that the adjustment of the stones can be quickly made for grinding coarse or fine material; that the construction as a whole is simple, cannot readily get out of order, 10 can be manufactured at low cost and can be operated by an unskilled person.

I claim:

15 A feed regulator for a grinding mill comprising in combination, a frame, a shaft horizontally supported by said frame, an enlarged collar formed upon said shaft having spirally formed spaced feeding ribs said collar serving as a stop limiting the movement of said shaft in one direction, a hopper

having a discharge opening located forward of said collar said hopper ending in an oblique front bottom portion, a tray having an oblique front portion arranged for coaction with said oblique hopper bottom portion and ending in a lip at its inner end arranged to alternately ride upon said collar and ribs, and a pivot passing through said oblique tray portion to said oblique hopper portion, whereby said tray is pivotally supported at its forward end, as, and in the 20 25 30 manner set forth.

In testimony whereof I affix my signature, in the presence of two witnesses.

MELTON MORRIS.
